PULVERIZER

Louis R. Kuhlengel, St. Louis, Mo., assignor to
 Williams Patent Crusher and Pulverizer Company, St. Louis, Mo., a corporation of Missouri

Application July 14, 1934, Serial No. 735,147

6 Claims. (Cl. 83—11)

This invention relates generally to pulverizers and more particularly to feeding means therefor.

In operating grinders to pulverize to a finely ground state clay, coal, lime, mica, cinnamon and other material, it is desirable to interpose closure means between the feed hopper and the grinding chamber in order to prevent the finely ground material from backing up or escaping from the feeding chamber into the feed hopper. 10 The main objects of this invention are to provide a feeding means which operates between the feed hopper and the grinding chamber and includes a feed trough having a gate or closure plate adjacent to the grinding chamber and which is normally closed and is opened to permit the discharge of material into said grinding chamber when a sufficient amount of material has accumulated in the feed trough.

Other objects of the invention are to provide 20 a feeding mechanism including a feed trough, the discharge end of which is provided with a closure member, said discharge end being provided with an upwardly turned lip which serves to arrest the material in the trough until a sufficient amount has accumulated therein, whereupon the accumulated material is discharged from said trough into the grinding chamber of the grinder, thereby opening said plate to effect the discharge of material.

Further objects of the invention are to construct the feed trough and the feed hopper in a single casting whereby said feed trough can be readily attached to and detached from the grinding machine without the necessity of dismantling the latter, and to provide a removable plate in said grinding machine to permit ready access to the closure plate of said feed trough for the purpose of observation or to serve as a clean-out.

With these and other objects in view, my invention consists in certain novel features of construction and arrangement of parts, hereinafter more fully described and claimed and illustrated in the accompanying drawings, in which—

Figure 1 is a longitudinal vertical cross section of a grinding machine equipped with my improved feeding means.

Figure 2 is a vertical transverse cross section taken on line 2—2 of Figure 1.

Figure 3 is a vertical cross section taken on line 3—3 of Figure 1.

Figure 4 is a vertical cross section taken on line 4—4 of Figure 1.

Figure 5 is a reduced top plan view of the feed hopper and feed trough casting.

Figure 6 is a longitudinal cross section taken on line 6—6 of Figure 5.

Figure 7 is a rear end elevational view of same.

Referring by numerals to the accompanying drawings, 10 indicates a grinder, 11 the feed hopper, and 12 the feeding means by means of which the material to be pulverized is fed from the hopper to the pulverizer. In the instant case, the pulverizer is shown as being of the hammer-mill type including a casing 14 having a grinding chamber 15, a revoluble shaft 16 journaled in said casing, and a plurality of hammers 17 pivotally mounted on spacer disks 18 which latter are fixed on said shaft within said grinding chamber.

Casing 14 is provided with a cover 19 hinged at 20. This cover forms an opening 21 in which is received the forward or discharge end 22 of a horizontally disposed trough 24. The latter is preferably formed as a single piece casting 20 with hopper 11, as shown in Figures 5 to 7, and the lower end of said hopper opens into said trough. One or more troughs may be used and where a plurality of troughs is used they are arranged side by side as in the instant case, 25 where three troughs are used.

The rear or outer end 25 of each trough extends past the lower end of the hopper and terminates in a lateral flange 26, the upper portion of which is merged with the rear inclined wall 30 of the hopper as indicated at 26a. The forward or discharge ends 22 of the trough extend a suitable distance past the front wall of the hopper and enter opening 21 formed in grinder 10.

Where a plurality of troughs is used they are 35 separated from each other by a longitudinally disposed partition wall 27 which is formed integral with the casting. The forward or discharge end of the trough casting has formed integral therewith a transverse wall 28 which extends upwardly a suitable distance above the bottoms of the troughs. The inner side of this wall is inclined upwardly and forwardly, as indicated at 28a. The outer side is disposed vertically at its lower portion, as indicated at 28b, while the upper 40 portion is inclined upwardly and rearwardly, as indicated at 28c. The angle of inclination of portion 28c is the same as that of closure plates 29 which close the discharge ends of the troughs. Preferably a separate closure plate 29 is provided 45 for each trough so that they can operate independently of each other. Each plate is pivotally mounted at its upper end by means of a pin 30. Preferably a single pin is used for all of the plates and the ends of said pin are secured to the side 50 55

walls 31 of the trough casting. Each plate is held in closed position against the respective end of the feed trough by gravity. Thus the communication between the grinding chamber and the troughs and the hopper is normally closed and the dust and finely ground material contained in the grinding chamber cannot enter the hopper.

The raised wall or lip 28 in each trough serves to retain the material therein until sufficient amount has accumulated, whereupon said material is forced from the trough, thereby temporarily displacing the closure plate. As soon as the material has been discharged from the hopper, the respective closure plate by virtue of gravity assumes its normal closed position.

The material is fed forwardly in each trough by means of a screw conveyor 32 operating therein. This conveyor is mounted on a horizontally disposed shaft 34 which is journaled in a bearing 20 35 fitting into the rear end of the trough casting and formed integral with a gear housing 36. The latter is bolted to flange 26 of the trough and hopper casting and its outer open end is closed by a plate 37 detachably secured thereto in any suitable manner.

The shafts 34 are interengaged by means of intermeshing gears 38 which are fixed on said shafts within said housing. In the present instance, the intermediate shaft terminates within said housing, as indicated at 34a in Figure 1, while the two outer shafts have their ends journaled in bearings 39 formed in plate 37. One of the outer shafts has fixed thereon a large beveled gear 40 and meshing with this is a small beveled pinion 41 which is fixed to a shaft 42. This shaft is journaled in a bearing 43 and extends from said housing at right angles to conveyor shafts 34 and is driven in any suitable manner.

Cover 19 is provided with an elongated opening 44 and the top wall of the trough extension is provided with a similarly shaped opening 45. When the hopper and trough casting is in place on the grinder, these openings coincide and are adapted to receive a box-shaped cover 46 which is secured in position on cover 19 by bolts 47 and extends inwardly into engagement with opening 45. When it is desired to observe the action of the respective closure plates 29, said cover 46 can be removed. The grinder is provided with the usual cage 48 through which the ground material is discharged from the grinding chamber.

As stated before, hopper 11 and feed trough 24 are formed integral with each other in a single casting. This casting is secured to the grinder 55 by bolts 49 which engage flanges 50 of casing 14 and are screw-seated in a pad 51 formed integral with the underside of the forward end of trough casting 24. Additional supports for the casting are provided by means of studs 52. The upper 60 end of hopper 11 is flanged and can have secured thereto a material feed duct (not shown).

In the operation of the machine, the material to be ground is deposited into the hopper 11 and is discharged therefrom into the respective feed troughs 24. The screw conveyors 32 operate in said troughs and move the material toward the forward end where it accumulates against the lip or transverse wall 28 and against the closure plate 29. Due to said lip and to the weight of the closure plate a certain amount of material has to accumulate in each trough before the closure plate thereof opens to permit the discharge of the material into the grinding chamber 15. As soon as this discharge takes place the closure plate by virtue of gravity assumes its normal closed posi-

tion. Thus it will be noted that the closure plate is moved into open position at definite intervals and only upon the discharge of the material from the feed trough into the grinding chamber. At all other times the closure plate closes the communication between the grinding chamber and the feed troughs and the hopper.

Thus the dust laden air contained in the grinding chamber cannot escape by way of the feed troughs and the hopper and the discharge of material into the grinding chamber is not interfered with. The hopper and the troughs being formed integral in a single casting facilitate assembly thereof and attachment to the grinder and the mounting of the feed mechanism in said casting. The hopper and trough casting can be removed from its position on the grinder simply by removing bolts 49 and the cover 46 without the necessity of dismantling the grinder or any part thereof. 20

Preferably each closure plate 29 is provided with a weight 29a or other means for urging said closure plate into closed position.

The material can be conveyed to the hopper 11 by a suitable conduit attached to said hopper 49 25 as indicated in dotted lines in Figure 1. The lip 28 prevents continuous discharge of material from the trough and the subsequent continuous open position of the closure plate and the latter is opened only at regular intervals when the periodical discharge of material takes place. 30

By making the feed hopper and the feed troughs in a single piece casting and by forming the casing of the grinder in such a manner that this casting can be readily applied thereto, the cost of assembling is reduced to minimum and the grinder is rendered inoperative only for a short length of time.

While I have shown and described herein the preferred form of my device, it is obvious that various changes in the construction thereof can be made without departing from the spirit of my invention. 40

I claim:

1. In a grinder, the combination with a grinder 45
casing having a grinding chamber, of a feed
trough having its discharge end extending
through an opening in said casing into said
grinding chamber, an upwardly projecting lip
transversely formed in the discharge end of said 50
feed trough to cause accumulation of material
therein, the inner side of said lip being inclined
upwardly and outwardly, and a closure plate pivot-
ally mounted at its upper end above said dis-
charge end and extending downwardly against 55
said lip for closing said discharge end of said
feed trough, said closure plate being movable into
open position upon the discharge of material
accumulated in the discharge end of said feed
trough. 60

2. In a grinder of the class described, the combination of a casing having a grinding chamber and an open-ended extension, a feed trough having its forward end extending into said extension and opening into said chamber, a transverse lip formed on the bottom of said forward end of said trough and projecting upwardly a suitable distance to cause accumulation of material in said end and to cause the discharge of said material at spaced intervals, and a closure plate pivotally mounted on said forward end and overlapping said lip and closing said end to prevent communication between said grinding chamber and said trough, said closure plate being displaceable

from its closed position by the material discharged from said trough into said chamber.

3. In a grinder, the combination of a casing having a grinding chamber and an open-ended extension, a feed hopper, a feed trough having its rear end communicating with said hopper and having its forward end extending into said extension and opening into said chamber, an upwardly projecting lip formed on the bottom of the forward end of said trough to cause the discharge of material therefrom at spaced intervals, a screw conveyor in said trough for feeding the material toward said forward end thereof, and a closure plate mounted on said forward end of said feed trough and normally held in engagement therewith and overlapping said lip to close the communication between said chamber and said feed trough, said closure plate being displaceable by the material upon the discharge thereof from said trough.

4. In a grinder, the combination of a grinder casing having an open-ended extension, a feed trough having one end extending into said extension and opening into said casing, means for conveying material through said feed trough, an upwardly projecting lip formed on the bottom of the inner end of said trough to cause the discharge of material into said casing at spaced intervals, and a closure plate pivotally mounted on the forward end of said feed trough forwardly of and above said lip for closing said end and preventing communication between said trough and said chamber, said plate being displaceable into open position by the material discharged from said feed trough into said casing.

5. In a grinder, the combination with a casing having a grinding chamber and an open-ended extension, of a unitary structure comprising a

feed hopper and a feed trough, said feed trough extending into said extension and having its discharge end opening into said grinding chamber, a transverse lip formed on the bottom of said discharge end of said trough to retard the discharge of material therefrom, said lip having its inner face inclined forwardly and upwardly, means for removably securing said structure in position on said casing, a closure plate pivotally mounted on the forward end of said trough and overlapping said lip, thereby closing said feed trough and preventing dust from escaping from said grinding chamber into said trough, said closure plate being movable into open position by the material discharged from said trough, there being formed in the juxtaposed walls of said extension and said trough coinciding openings to provide access to said discharge end, and removable means for closing said openings.

6. In a grinder, the combination with a casing having a grinding chamber and an open-ended extension, of a feed trough removably secured to said extension and having its discharge end opening into said chamber, a feed hopper arranged above the other end of said trough and opening thereto, a material conveying means in said trough for forcing the material toward the discharge end thereof, an upwardly and outwardly inclined lip formed transversely on the bottom of said discharge end to cause discharge of material at spaced intervals, a closure plate movably mounted on said discharge end and yieldably closing the same, the lower end of said plate overlapping said lip, whereby dust is prevented from escaping from said grinding chamber, said plate being displaceable by the material discharged from said trough.

LOUIS R. KUHLENGEL.
